UNITED STATES PATENT OFFICE

LOUIS C. STUKENBORG, OF MEMPHIS, TENNESSEE

HYDRAULIC JACK

Application filed November 12, 1930. Serial No. 495,068.

This invention relates to lifting jacks, in which the raise of the plunger is accomplished through the medium of a liquid, ordinarily oil, and especially to lifting jacks

5 used for raising automobiles for the purpose of servicing them, in which the jack comprises an elongated cylinder which is disposed in a hole dug in the ground whereby the cylinder is not readily accessible after it 10 has been put in place, and which jack employs a correspondingly elongated piston or plunger and heavy super-structure carried by the plunger, which latter unit by reason of its size, shape and weight, is extremely difficult 15 to remove from the cylinder.

It further relates to a device of this character in which the entire actuating mechanism is disposed within and carried by the plunger, whereby extraneous pipes or other 20 connections to inaccessible portions of the cylinder are avoided.

The present invention particularly relates to means for accomplishing accessibility of all the actuating and control parts of the 25 device without the necessity of removing or of handling those heavier parts, namely, the plunger assembly and the cylinder.

In jacks of the type referred to the plunger employed is hollow and forms a reservoir 30 for the oil used for lifting purposes. It also forms a casing which encloses as well as carries the pump and motor by which the oil is transferred from the plunger to the cylinder to accomplish raising of the plunger.

35 The primary object of the present invention is:

To make a self-contained removable unit 40 of the pump, motor, and release mechanism which may be inserted and secured within the plunger as a unit, and, as a unit be removed therefrom for servicing and repair.

A further object is to provide means for connecting and disconnecting the pump from the plunger whereby delivery of the oil from 45 the pump to the exterior of the cylinder is accomplished, which connecting means will permit the ready removal from, and replacement of the pump unit within, the plunger.

The means by which the foregoing and 50 other objects are accomplished and the man-

ner of their accomplishment will readily be understood from the following specification on reference to the accompanying drawings, in which:

Fig. 1 is a sectional elevation taken on the 55 vertical center line of the plunger and cylinder showing the preferred form of my device.

Fig. 2 is an enlarged sectional elevation showing a detail of the means by which the 60 connection is made between the pump discharge and the discharge pipe leading therefrom to the outside of the plunger.

Fig. 3 is a section identical to Fig. 1, except that it shows a modified form of the 65 connection between the pump and the discharge pipe.

Fig. 4 is an enlarged fragmentary sectional elevation showing the detail of the means 70 employed in making this connection.

Fig. 5 is an additional sectional elevation on the center line of the plunger and cylinder showing an additional modification of the means for connecting the pump and the 75 discharge opening between the plunger and cylinder.

Referring now to the drawings in which the various parts are indicated by numerals, 10 is a vertical cylinder having a closed bottom end 11, which cylinder is disposed with 80 its upper end at the surface of the ground, and substantially the entire cylinder below the ground. 12 is an annular plunger guide and 13 a stuffing box and packing at the upper end of the cylinder. Disposed within this cylinder is a plunger 14 comprising a hollow cylinder, closed at its lower end by a head 15 which is preferably welded in place. Integral with the upper end of the plunger is 85 an annular flange 16 to which is secured a head 17, as by bolts 18, and which head carries rails 19 such as are now commonly used in vehicle lifts, and which are usually designated as a table. This table may be of any desired type such as the free-wheel type, being that shown, or the wheel-supporting type, or of any other desired conformation, the detail of the head and table not being a part 90 of the present invention.

The upper end of the plunger is closed by a 100

removable plate 20, preferably held in place by cap screws 21. Secured to and supported by this plate is an electric motor 22 the wiring and source of power not being shown since it is of usual type. The motor may be integral with the plate or it may be secured thereto as by bolts or cap screws 23. Depending from the motor are posts 24 to which a pump 25 is secured as by the bolts or cap screws 26. 27 10 is the motor shaft, 28 the pump shaft and 29 a coupling securing them together.

The pump is provided with a suction inlet 30 from which a depending pipe 31 is carried downward within and substantially to the 15 bottom of the plunger. Preferably the lower end of this pipe is provided with a screen 32. The pump also has a discharge outlet 33 which has been brought to central position, beneath and in axial alignment with the 20 pump and motor shaft. 34 is a short nipple secured in this opening and 35 a check valve secured on this nipple. Disposed below and carried by this check valve, is a T 36 from the lower end of which a pipe 37 extends 25 downward, this pipe forming part of the means by which connection is made between the pump and a discharge pipe 38 which leads downward through the head 15 of the plunger and which discharges outside the plunger. 30 Slidably mounted on the pipe 37, is a stuffing box 39, in which box is disposed packing 40 which surrounds the pipe 37. The stuffing box 39 is internally threaded adjacent its lower end and is preferably provided below 35 such threaded portion with a flared skirt 41. The upper end of the discharge pipe 38 is provided with a thread, complementary to the stuffing box thread, whereby the stuffing box may be engaged over the pipe 38 and 40 screwed down thereon to compact the packing 40 and make a sealed joint between the pipes 37 and 38.

Secured to and depending from the pump 25 are arms 42 which extend downward outside of the stuffing box 39 and which arms engage forked lugs 43 which are integral with the stuffing box. In order that there may be no possibility of displacing the stuffing box with reference to these arms, pins 50 44, preferably cotters, are passed through the lower ends of these arms.

Leading laterally from the T 36 is a nipple 45 on which is mounted a release valve 46 from which a control rod 47 leads upward 55 through the plate 20. The detail of the release valve and the operating mechanism for the control rod not being a part of the present invention are not here shown.

The pump, motor, check valve, and release 60 valve constitute the parts of this device which under ordinary circumstances need repair. In the description just set out and in the following descriptions they constitute a unit which may be readily removed to accomplish 65 such repair.

Ordinarily the plunger with this unit in place is shipped from the factory ready for installation. Thereafter in case repairs are necessary or if for other reasons, it is desired to remove the unit the cap screws 21 are removed freeing the plate 20. This plate may then be turned, thereby turning all the parts of the unit and the gland 39 be unscrewed from the pipe 38 after which the entire unit may be lifted out of the plunger and become 70 accessible for such purposes as may be desired. 75

After repairs have been made the unit may be replaced in the plunger. As the unit is lowered the skirt 41 is easily engaged over the end of the pipe 38 thus centering the device and guiding the pump and plunger discharge pipes into alignment, and the gland may then be screwed tight compacting the 80 packing 40 and sealing the joint between the 85 pipes 37 and 38.

It will be noted that provision is also made by such a joint for inequalities of pipe lengths since the packing 40 and its surrounding gland may occupy any portion of the length 90 of the pipe 37. It will of course be understood that the detail of the joint between these pipes is illustrative only and is intended merely to typify a packing joint tightened in the manner shown. 95

In Figs. 3 and 4, I have shown a modified form of the device in which a pipe 37A extends downward from the T 36 this pipe being provided with a flange 50 which forms an abutment for packing 51. If desired, an additional flange 52 may be employed to support the packing on the pipe. The outside diameter of the flanges 50 and 52 is less than the inside diameter of the discharge pipe 38A which is used in this case. 53 is a flared skirt on the upper end of the pipe 38A. In Fig. 4, the pipe 38A is shown as the packing is beginning to seat against the inner wall of the pipe 38A. The joint in this case is made by forcing the pipe 37A downward thus compressing the packing 51 between the outside of the pipe 37A and the inside of the pipe 38A. It will be noted in this case also that compensation is provided for variations in pipe length. In this form of the device the cap screws 21 which hold the plate 20 down serve also to hold the joint during use. In removing this form of device the cap screws are loosened and the unit as before described, is raised thus withdrawing the packing and freeing the joint. In replacing the unit the lower end of the pipe 37A is engaged in and guided by the skirt 53 so that installation is easily accomplished, and the completion of the installation is accomplished by screwing down the cap screws 21 which hold the plate 20 in place. 100 105 110 115 120 125

In the first described form it is essential that the pipes 37 and 38 be centrally disposed in the plunger in the form thus described, this 130

is also preferable in this case but not essential. In Fig. 5, I show a further modification in which a flexible pipe 60 is used instead of the discharge pipe 38 or 38A as the case may 5 be. This discharge pipe is connected by a union 61 to a nipple 62 which leads from the T 36 between the check valve 34 and the release valve 46. The length of the pipe 60 is made sufficient to permit the entire unit to 10 be raised until the union is above the top of the plunger and is thereby made accessible so that it may be connected or disconnected. In removing the unit when using this form of device the cap screws are loosened, the unit is 15 raised until the union is in the clear and the pipe 60 then disconnected. In replacing the device the union is first connected and tightened and the unit thereafter lowered into the plunger and secured as before. It will be 20 noted in this type of device that it is immaterial whether the discharge opening on the pump is in the bottom or at the side thereof.

It will be noted in all of the forms shown 25 that the pipe connection is extensible, to a greater or less extent, and that accomplishment of the coupling is made possible by detachment of the jack-actuating unit from the plunger.

Having described my invention, what I 30 claim is,

1. In a hydraulic jack, an elongated hollow plunger closed at its lower end and forming a reservoir for the lifting liquid, said end having a centrally disposed discharge opening therethrough, a lift-actuating unit adapted to be disposed within and carried by the upper end of said plunger, said unit including a pump, and rendering the lower end of said plunger inaccessible; and means for connecting said plunger opening and the pump discharge comprising a pipe extending longitudinally upward from said opening along the center line of said plunger, a pipe extending downward from said pump, one of said 35 pipes telescoping within the other thereof, a coupling part similarly slidable along said first pipe, complementary coupling means on the other of said pipes, and means carried by and actuatable through said lift unit for 40 accomplishing connection and tightening of said coupling parts.

2. In a hydraulic jack, an elongated hollow plunger closed at its lower end and forming a reservoir for the lifting liquid, said end 45 having a discharge opening therethrough, a lift-actuating unit adapted to be disposed within and carried by the upper end of said plunger, said unit including a pump, and means for connecting said plunger opening 50 and the pump discharge comprising a pipe extending upward from said opening, a pipe extending downward from said pump, one of said pipes telescoping within the other thereof, packing carried by one of said pipes, 55 and coacting with the other thereof, and

means carried by and actuatable through said lift unit for accomplishing compression of said packing to seal said pipes together.

3. In a hydraulic jack, an elongated hollow plunger closed at its lower end and forming 70 a reservoir for the lifting liquid, said end having a discharge opening therethrough, a lift-actuating unit adapted to be disposed within and carried by the upper end of said plunger, said unit including a pump, normally inaccessible means for connecting said plunger opening and the pump discharge comprising complementary separable coupling parts, connections, one from said pump to one part of said coupling and one from 75 said opening to the other part of said coupling, means for guiding said coupling parts into alignment, and means actuatable through said unit slidably engaging one of 80 said coupling parts for actuating it to accomplish connection of said parts.

In testimony whereof I hereunto affix my signature.

LOUIS C. STUKENBORG.
